CLAIM

The ornamental design for a hose and ferrule assembling apparatus, substantially as shown.

DESCRIPTION

FIG. 1 is a perspective view of a hose and ferrule assembling apparatus showing my new design;
FIG. 2 is a left side elevational view thereof;
FIG. 3 is a front end elevational view thereof;
FIG. 4 is a rear end elevational view thereof;
FIG. 5 is a left side elevational view thereof;
FIG. 6 is a top plan view thereof, the bottom being unornamented.
